PROCESS FOR RECOVERY OF CYCLO-PENTADIENE

Homer F. Johnson, Jr., Union, N. J., assignor to
Standard Oil Development Company, a corpora-
tion of Delaware

Application August 25, 1947, Serial No. 770,456

7 Claims. (Cl. 260—666)

1

This invention relates to a practical method of obtaining monomeric cycloalkadienes of high purity from cracked petroleum oils. More particularly it relates to an improved process for the recovery of high purity cycloalkadiene monomers by means of liquid phase depolymerization of cycloalkadiene polymers contained in low concentrations in an aromatic naphtha.

Cyclopentadiene is a highly reactive cyclic diene which has a potentially large scale demand for use as a modifier for drying oils, as a reactant in the manufacture of resinous copolymers and in the preparation of textile impregnating agents. Additional suggested uses are dependent upon a commercially available supply in a relatively pure state. Commercially available supplies in the past have been of only limited purity.

There has grown up during recent years a demand for normally gaseous unsaturated hydrocarbons such as ethylene and butadiene. Intensive cracking processes have been developed for converting large proportions of petroleum feed stocks to these gases. These processes also yield naphtha distillates that contain considerable amounts of aromatic compounds mixed with unsaturated hydrocarbons. An intermediate distillate fraction, such as a cycle gas oil, and a heavy tar are also obtained. Conditions favorable for obtaining high yields of unsaturated hydrocarbons and aromatics in cracking volatile petroleum stocks are high temperatures of the order of 1200 to 1500° F. and low pressures of the order of 1 to 10 atmospheres.

The charging stock for this operation is fed to the cracking zone where it may be diluted with up to 90% mol percent of steam in order to restrict carbonization. The hot cracked product issuing from the cracking zone is quenched and fed to a fractionating tower. The naphtha fraction and steam are then taken off overhead leaving the residual oils which are taken off as tarry bottoms and a cycle gas oil which is taken off as a side stream. The fractionated naphtha and steam are cooled and a water layer is separated. By processing the highly cracked products in the manner described, the cycloalkadienes are found in this naphtha fraction mainly as polymers. The amount of cycloalkadiene polymers in this final naphtha fraction seldom exceeds 12%.

Depolymerization of the dimer has been performed directly on this naphtha feed after the conventional debutanization as one of the steps in separating the cycloalkadienes from this fraction. This has necessitated vapor phase depolymerization of the dimers, as liquid phase treatment of this wide cut distillate boiling from 175 to 400° F. is impractical. Vapor phase heating requires either the use of a furnace to bring the feed up to about 700° F. or else extremely long vapor holding time at some lower temperature. 60

2

In either case vapor phase cracking of this naphtha distillate is a relatively high cost operation, and requires expensive equipment, including additional equipment for separating impurities.

5 The vapor phase depolymerization of cycloalkadienes in a wide naphtha fraction is difficult to control, and necessitates repolymerization of the monomer for obtaining separation of other cracked components. Because some of these other components, i. e. other C 5 diolefins and some C 6-8 constituents, polymerize also, the purity of the desired dimer is considerably reduced.

An object of this invention is to provide an improved commercially feasible process of obtaining cycloalkadienes such as cyclopentadiene and its homologs, each in a substantially pure state directly from an aromatic naphtha fraction produced in petroleum cracking. Another object is to provide a process wherein liquid phase depolymerization of cycloalkadiene monomer can be advantageously used to obtain pure products with restricted decomposition of other components in the naphtha. Another object of this invention is to provide a more rapid and efficient liquid phase process for depolymerization of cycloalkadiene polymers. Other objects will be apparent to those skilled in the art.

This invention is a method of separating and recovering a cycloalkadiene monomer such as cyclopentadiene from a cracked petroleum naphtha stock containing its polymers which comprises the steps of fractionally distilling the naphtha stock with steam to remove at least its C₁ through C₅ hydrocarbon but preferably its C₁ through a major proportion of its C₅ hydrocarbons to leave a topped aromatic fraction boiling about 350° F., heating the topped aromatic fraction at its boiling point in the liquid phase in a heat treating zone to depolymerize the dimers, stripping with hot vapors to remove cycloalkadiene monomers from the hot aromatic fraction as rapidly as formed, quickly fractionally distilling the overhead product so that substantially all of the monomer is taken off overhead and returning heavier materials containing any repolymerized monomer to the heat treating zone for further depolymerization.

Having outlined the process of this invention in a general manner, further specific details will be explained with reference to the accompanying drawings.

Fig. 1 is a flow diagram which schematically illustrates means and steps in carrying out a preferred embodiment of this invention.

55 Fig. 2 is a vertical section of a two-stage heating zone 23 of Fig. 1 shown in further detail.

In the flow diagram 1 represents a high temperature steam cracking zone into which a petroleum cracking stock is charged from line 2

and steam or preheated water is supplied from line 3, the charging stock being in the liquid or preheated vapor condition. The cracking zone may be contained in a fired pipe coil or other conventional type of cracking apparatus. Steam or preheated water may be supplied at a multiplicity of points to the coil. The cracked products leave the cracking zone through line 4 and are promptly quenched by introduction of cool liquid cycle oil introduced by line 5 into line 4. The quenched cracked products are discharged from line 4 into a fractionating zone 6 from which cracking tars are withdrawn through line 7, and liquid cycle oil is withdrawn as a side stream, line 8. Cracked naphtha vapors together with steam and gases are drawn overhead from fractionating zone 6 through line 9 and are passed through cooling condenser 10 into a separation zone 11. Uncondensed gases leave the separation zone through line 12. Water condensate is removed from the bottom of the separation zone through line 13 and naphtha distillate which may include varying amounts of condensed C₁ to C₁₂ hydrocarbons is withdrawn through line 14 from the separation zone 11 to a fractional distilling means 15.

The uncondensed gases withdrawn from the separation zone 11 through line 12 may be compressed in compressor 16 partially condensed in condenser 41, and sent to separator 42. Inert non-condensable gas is withdrawn overhead through 43 and the condensate is combined by line 17 with the distillate supplied to the fractionating means 15 for the common fractionation therein.

This feed to fractionator 15 conventionally is first debutanized and the overhead fraction used as a feed for other processes.

In the fractionating means 15, the naphtha distillate is kept at as low a temperature as possible during removal of C₄ through C₇ hydrocarbons to minimize decomposition of cycloalkadiene polymers. Live steam is introduced through line 18 in order to lower the distillation temperatures of the hydrocarbons to be stripped. The gases taken overhead through line 19 comprise up to C₈ hydrocarbons, steam, very little cyclopentadiene monomer and some aromatics. This overhead fraction may then also be used as a feed for other processes, or fractionated elsewhere. The thus topped aromatic distillate is withdrawn as bottoms from the fractionating tower 15 through line 20, and advantageously free from any water, is passed through heater 21 and then to a two-stage heating zone 23 through line 22.

The withdrawn bottoms from fractionator 15 is generally at a temperature of about 250-275° F. The heater 21 brings the temperature up to about 330-350° F., and the thus heated bottoms are transferred through line 22 to a point near the top of the first zone 24 of the two-zone heating means 23. (Shown in detail in Fig. 2.) The thus heated bottoms accumulate in the first zone 24 until the liquid exceeds the height of the entrance to the liquid downcomer 25. The liquid continuously thereafter flows down to the second stage of the heating zone 26, is heated by reboilers 27 and 28 to about 350-380° F. and returns through lines 29 and 30 to the second heating zone 26. The liberated monomers rise along with other vapors through vapor line 31 and are bubbled through the liquid in the first stage by means of perforated plate distributor 35, which is located above solid plate 44, which separates the two zones. This accomplishes strip-

ping of the cyclopentadiene formed in the first stage. Operating conditions for the first stage are preferably 320-360° F., pressure conveniently 4 p. s. i. gauge, and for the second stage 340-375° F., conveniently 10 p. s. i. gauge. The remaining high boiling naphtha freed of polymers of cyclopentadiene and its homologs is withdrawn from heating zone 23 as bottoms by line 37. The usual duration of this described heat treatment in the liquid phase is four to eight hours.

The vapors taken off overhead by line 32 are condensed by condenser 33 to below 300° F. and are then taken to fractionating means 34. The monomers are cooled as quickly as possible after depolymerization. The distillation of the heat treatment product following the condensation is carried out in such a manner as to minimize polymerization of cycloalkadiene monomer, and preferably follows the condensing immediately. Hold-up time in the distillation and fractionation is minimized. The temperature of overhead vapors from fractionating means 34 should not exceed 120° F. and preferably runs about 106° F. or lower depending on cooling water temperature available. The bottoms from fractionating means 34 are recycled by line 36 by means of a pump or gravity flow to the first stage 24 of a heating zone 23 and any redimerized monomer is not lost.

The cyclopentadiene vapors are withdrawn overhead from fractionating means 34 through line 38 and cooler 39 into receiver 40 for the cyclopentadiene monomer cut. Higher boiling homologs may also be withdrawn.

Particular points of interest in the preceding detailed description are as follows:

In the removal of the C₄ to 90% C₈ material in fractionator 15 steam distillation is used. Removal of these hydrocarbons is highly desirable so that substantially pure monomer can be recovered and more efficient operation can be obtained in the subsequent operations. It has been found that if only a small portion of feed stock were topped in the fractionation, i. e., C₄-10% C₈, the lighter hydrocarbons would later appear in significant quantities in the vapor being removed from heating zone 23. Increasing the hydrocarbons taken overhead from C₄ to 10% C₈, to C₄ to 90% C₈ reduces the amount of vapor subsequently taken overhead from the heating zone 23 by a factor of about 15. This results in a decrease in the vapor requirement to remove monomer from the heat treating zone and consequently necessitates less heat input. Lower pressures can then also be used. In addition the increased concentration of the cycloalkadiene polymer greatly decreases the holdup volume required in the heat treating zone.

Live steam is thus fed into fractionator 15 in order to secure the removal of C₄ through 90% C₈ material without danger of dicycloalkadiene depolymerization. At a bottom temperature of 284° F. only 0.1 of one percent cyclopentadiene monomer is found in the overhead product. If this temperature exceeds 300° F., as much as 5% monomer can be found in the overhead product. Vapor pressure of water at 284° F. is 37.7 p. s. i. gauge and a tower operated at this pressure cannot reach a temperature above this figure as long as a liquid water phase is present. When the tower is kept at 266° F., 26 p. s. i. gauge, however, up to 90% of the C₈ hydrocarbons are removed. The amount taken overhead in this separation was 73 volume percent of the debutanized feed going to this tower.

The feed going to the heating zone 23 comprises largely alkyl substituted aromatic homologs of benzene and cycloalkadiene polymers. The initial boiling point of this aromatic fraction is about 365° F. The higher concentration of dimer in this aromatic naphtha due to the prior removal of C₁ through 90% C₈ hydrocarbons enables the depolymerization of the dimer to proceed much more rapidly in the heat treatment. The use of the two heating zones 24 and 26 also contributes to this more rapid operation. The dimer concentration in the first zone 24 is higher than in the second zone 26. The formation of the monomer thereby proceeds more rapidly. It is necessary to almost completely remove the monomer to prevent its repolymerization. The vapors from the liquid in the second zone sweep through the liquid in the first zone and the monomer is removed rapidly overhead, thus preventing its redimerization. The amount of vapor required to remove the monomer from the upper section of the reactor increases with any increase in the lighter before mentioned hydrocarbons in the feed. Using two stages instead of one in heating zone 23 in order to depolymerize 90% of the dimer, reduces the required heating time by about one-half. The described stripping of monomer vapors as formed from heating zone 23 can also be accomplished by the use of steam or any inert gas.

A multi-stage process may be used instead of a two stage heating zone. The vapors from each stage may be bubbled up through the liquid of the preceding stage, heat being put only into the last stage. This is equivalent to a counter current stripping operation.

The fraction taken overhead from tower 34 depends on the product desired, thus a cut through C₅, C₆ or C₇ may be taken overhead depending on the final product desired. It is desirable to keep this polymerization in the final tower to a minimum. This is accomplished by designing the tower for minimum holdup and minimum temperature of operation in the upper section where the monomer is concentrated.

In a manner similar to that described for obtaining the cyclopentadiene monomers, its homologs such as methyl cyclopentadiene, dimethyl cyclopentadiene and cyclohexadiene can also be separated and recovered from the cracked petroleum products.

Experimental data were obtained in investigating cyclopentadiene monomer recovery in a two stage heating zone operation performed in the manner described and the tabulated results are presented in the following table:

TABLE

Liquid phase cyclopentadiene recovery

Heating Zone Residence Time, Hours	Temperature Range in Heat Treating Zone	Product Yield, Vol. Percent	Product Purity, Mol Percent
7.4	366-367	8.8	92
7.4	368-375	9.8	91
7.4	364-377	10.3	92
6.9	368-377	11.3	92
6.4	370-378	10.6	92
5.66	364-372.5	8.8	92.3
5.17	355-358	11.6	91.8
4.0	357-372	9.05	93

Product purities of 91 to 93% were obtained with product yields of up to 11.6% based on feed to the heating zone.

This invention has been described with respect

to preferred modifications and adaptations but it is to be understood that other modifications come within the scope of this invention as defined in the appended claims.

5 I claim:

1. A continuous process for forming and separating a monomeric cycloalkadiene from a cracked petroleum naphtha fraction containing the cycloalkadiene dimer, said naphtha fraction having been topped to remove monomeric diolefins and C₇ and lower hydrocarbons that boil below 350° F., which comprises passing said topped fraction containing substantially the same amount of the cycloalkadiene dimer as was present in the naphtha fraction prior to the topping to the first of a series of two heating zones where this dimer undergoes depolymerization, the first zone being in communication with a second heating zone so as to supply a residual liquid portion of the topped naphtha fraction continuously thereto; heating said residual liquid portion from the first heating zone in the liquid phase in the second heating zone to depolymerize the cycloalkadiene dimer which said residual liquid portion contains and to form vapor of its monomer; sweeping hot vapor containing the monomer vapor from said second heating zone to said first heating zone to strip additional cycloalkadiene monomer therefrom, taking off the combined vapors from said first zone to a fractionation zone separate from any zone in which initial naphtha fraction is topped; fractionating the cycloalkadiene monomer from the vapors entering said fractionation zone in the absence of C₇ and lower hydrocarbons other than cycloalkadiene monomer to obtain a distillate product of the monomer, and returning a bottoms portion from said fractionation zone to said first heating zone for further recovery of monomeric cycloalkadiene.

2. A continuous process for separating and recovering a monomeric cycloalkadiene from a cracked petroleum naphtha fraction containing the cycloalkadiene polymer, which comprises the steps of steam-distilling the cracked petroleum naphtha fraction to remove C₄ through C₇ hydrocarbons therefrom at below 300° F. so as to leave a topped aromatic fraction with negligible change in the amount of the cycloalkadiene polymer therein; passing said topped fraction to the first of the series of two heating zones, the first zone being in communication with a second heating zone so as to supply a residual liquid portion of the naphtha fraction continuously thereto; heating the residual liquid portion from the first heating zone in the liquid phase in the second heating zone to depolymerize the cycloalkadiene polymer and vaporize cycloalkadiene monomer; sweeping hot vapor containing the vaporized monomer from said second heating zone to said first heating zone to strip additional cycloalkadiene monomer therefrom; taking off the resulting combined vapors from said first zone to a fractionation zone separate from any zone in which initial naphtha fraction is topped through a cooling zone wherein said vapors undergo quick condensation, and fractionating the cycloalkadiene monomer in the absence of C₄ through C₇ hydrocarbons other than the cycloalkadiene monomer from the resulting condensate.

3. A continuous process for separating and recovering a monomeric cycloalkadiene from a cracked petroleum naphtha fraction containing the cycloalkadiene dimer with lower boiling di-

olefin monomers, which comprises the steps of distilling said lower boiling monomers and C₇ and lower hydrocarbons from the cracked petroleum naphtha fraction to leave a topped naphtha fraction containing substantially the same amount of cycloalkadiene dimer as contained by the naphtha prior to this topping step; passing said topped fraction to the first of the series of two heating zones, the first zone being in communication with a second heating zone, so as to supply a residual liquid portion of the naphtha fraction thereto; heating the residual liquid aromatic fractions from the first heating zone in the liquid phase in the second heating zone to depolymerize the cycloalkadiene dimer and form cycloalkadiene monomer vapor; passing vapor from said second heating zone to said first heating zone to strip additional cycloalkadiene monomer therefrom; taking off the combined vapors from said first zone to a fractionation zone separate from any zone in which initial naphtha fraction is topped; cooling the vapors as they pass to the fractionation zone and distilling the cycloalkadiene monomer in the absence of C₇ and lower hydrocarbons from the fractionation zone.

4. A process as in claim 3, in which a temperature in the range of 320° to 360° F. is maintained in the first heating zone and a temperature in the range of 340° to 375° F. is maintained in the second heating zone.

5. A process as in claim 3, in which the monomeric cycloalkadiene is cyclopentadiene.

6. A process as in claim 3, in which the monomeric cycloalkadiene is methyl cyclopentadiene.

7. A continuous process of forming and separating a monomeric cycloalkadiene from a cracked petroleum naphtha fraction containing the cycloalkadiene dimer, said naphtha fraction having been topped to remove monomeric

5
